UNITED STATES PATENT OFFICE

133,573

DESIGN FOR A DRESS

Simon Colin, New York, N. Y.

Application July 13, 1942, Serial No. 107,508

Term of patent 3½ years

To all whom it may concern:

Be it known that I, Simon Colin, a citizen of the United States and residing in Manhattan, in the city, county, and State of New York, have invented a new, original, and ornamental Design for a Dress, of which the following is a specification, reference being had to the accompanying drawing, forming part thereof, wherein

Fig. 1 is a front view of a dress showing my new design.

Fig. 2 is a rear view thereof.

I claim:

The ornamental design for a dress, substantially as shown.

SIMON COLIN.
